(57) **CLAIM**

The ornamental design for a mobile phone holder, as shown and described.

DESCRIPTION

FIG. 1 is a front perspective view of the mobile phone holder;

FIG. 2 is a rear perspective view thereof;

FIG. 3 is a front plan view thereof;

FIG. 4 is a rear plan view thereof;

FIG. 5 is a left plan view thereof;

FIG. 6 is a right plan view thereof;

FIG. 7 is a top plan view thereof; and,

FIG. 8 is a bottom plan view thereof.
